FABRIC GRIPPING CLASP FOR PENS,
PENCILS, AND THE LIKE

Eugène Marcoux, Coaticook, Quebec, Canada

Application November 4, 1948, Serial No. 58,333

4 Claims. (Cl. 24—11)

1

The present invention relates to an improved fabric gripping clasp for pens, pencils and similar articles, especially such articles as are carried in a pocket when not in use.

With the type of clasp or securing means for such articles now generally in use, it frequently occurs that a pencil, pen or other instrument accidentally slips out of a pocket and becomes lost owing to the fact that the usual flexible metal bar or clip loses some of its resiliency in time and hence does not maintain a tight grip upon the fabric of the pocket.

The main object of the present invention is to provide an improved clasp for such articles wherein the danger of the article falling from a pocket or losing its grip on the fabric to which it is attached is eliminated.

Another important object resides in the provision of a clasp of the character described wherein positive gripping means are provided to hold the article to the fabric of a pocket or to other places where it may be attached.

Still another important object resides in the provision of a clasp such as set forth above which may easily be affixed in place and removed therefrom, that is, it is a simple matter to render the clasp operable or inoperable relative to a fabric with which it is in proximity.

Another object resides in the provision of a clasp of the type set forth constructed in a single unit capable of being inserted into or removed from a pen, pencil or similar article having a barrel shaped casing.

Yet another object resides in the provision of a clasp of the character described which is simple in design and construction, may be relatively easily and cheaply manufactured, and yet is foolproof in operation.

Other objects and advantages will become apparent, or be further pointed out, in the description to follow.

As an example, and for purposes of illustration only, a preferred embodiment of my invention is shown in the annexed drawing, wherein:

Fig. 1 shows a perspective view of a fountain pen equipped with a clasp constructed according to the principles of this invention;

Fig. 2 shows a perspective view of that end of the fountain pen with which the clasp is associated, part of the construction being broken away in order to afford a better illustration of the clasp mechanism;

Fig. 3 shows a side elevation view of the upper portion of the fountain pen, the barrel of the latter being broken away and shown only in outline;

Fig. 4 shows a sectional elevation view corresponding to Fig. 2 with the clasp affixed in operative position relative to a fabric, and

2

Fig. 5 shows a similar sectional elevation view but with the clasp rendered inoperative.

Referring now to the drawing, wherein the same reference characters denote corresponding parts throughout, the clasp is seen to be associated with a fountain pen, the barrel of which is designated by 10, and consists of the usual clip member 11 at one end of the barrel and spaced laterally therefrom, and one or more pointed members 12 projecting from the interior of the barrel and co-operating with the clip to grip a piece of fabric therebetween.

Clip 11 and projecting members 12 constitute the main fabric gripping elements of the clasp, and it is further proposed that means be provided inside the barrel to urge members 12 outward into fabric-gripping position. In addition, other means are provided operable from the exterior of the article to retract the said pointed members inward. In a preferred embodiment of the invention, the pointed members 12 are secured at the free end of a bar 13 which is pivoted at its other end to a frame 14 on a pivot pin 18 secured to said frame. Members 12 will therefore project more or less out of the aperture 15 in the barrel according as to whether the lower extremity of bar 13 is swung towards or away from this aperture.

In order that the clasp normally retain its operative position, that is, that the fabric between the clasp and the pointed members normally be gripped tightly, a spring 16 is compressed behind bar 13 inside the barrel, or inside the clasp, to urge swinging of the bar to bring members 12 outward. At the extremity of the bar near the end of the barrel is formed a disc-shaped member 17 adapted to be enclosed in frame 14, whilst above the disc a button 19 is provided projecting beyond the barrel end. Accordingly, if pressure be exerted on the outer end of button 19, as by a finger, this will cause a pivoting of bar 13 (and hence of projecting members 12) inward as the button is also pressed inward. Obviously such pressure will be maintained upon the button as the pen or pencil is inserted into place in a pocket or the like, or when the article is being withdrawn therefrom.

Figs. 4 and 5 indicate the positions of the various parts of the mechanism when in operative position and inoperative position respectively, the fabric 20 being gripped or released according as to whether button 19 is released or pressed.

The drawings also indicate clearly how a unitary clasp, insertable into place in any article having an open ended cylindrical barrel with an aperture 15 and of appropriate dimensions, may be constructed. In this case, the clasp unit has a tubular frame 14 adapted to be inserted inside the barrel end and extending to a point be-

yond and in proximity with aperture 15. The exterior end portion of the frame 14 may be threaded to co-operate with corresponding threads on the inside of the barrel, and the outer extremity of the frame will be provided with a centrally-apertured shoulder portion 25 adapted to abut and close the barrel extremity. The clip member 11 is secured to portion 25 and extends longitudinally and spacedly of the barrel from this point. The bar 13 is carried inside frame 14 with the pointed projecting members 12 thereon, and this bar is pivoted at 18 to the frame near the outer end of the latter. An arm 26 is bent back towards the rear of bar 13 from disc 17 and this will increase the strength of the pivotable unit.

The force of spring 16 limits the inward displacement of bar 13. The disc 17 prevents the pointed members from being displaced too far out of the barrel and this disc underlies shoulder portion 25 of the frame.

Obviously such a unit may profitably be inserted in any pen, pencil or similar article having the requirements of an open ended barrel of appropriate dimensions to receive same. Moreover, existing articles may be adapted to receive the unit by the formation of an aperture 15 therethrough, and by drilling and packing one end of the barrel. In any event, such a unit will be found particularly satisfactory for articles produced in the future, whereby a unit may be removed for examination, adjustment or repair with very little trouble.

It will therefore be clear that the present invention fulfills the objectives hereinbefore set forth. Instead of relying upon a single clip, the resiliency of which becomes impaired with use, the present clasp embodies two co-operative members to grip the fabric therebetween, one of said members being continually urged into contact with the other by a coil spring of substantial size. At the same time, the positive means urging the members into operative position may be easily and quickly disengaged, in the present case by a button 19. The present clasp is thus a practical mechanism and at the same time an extremely simple one, having no parts requiring accurate machining or special manufacturing technique.

It will therefore be understood that I do not limit myself to the particular embodiment of my invention herein shown and described, since obviously various alterations might be made in the size, shape and arrangement of parts, without departing from the spirit of the invention or the scope of the subjoined claims.

Having thus described my invention, I claim:

1. A fabric-gripping clasp for pens, pencils and like articles having an open-topped barrel comprising, in combination, a clip member mounted on and spaced from the outside of the barrel adapted to contact one surface of the fabric, a pin extending from inside the barrel at a point near the lower end of the clip adapted to contact the other surface of the fabric and co-operate with said clip member in gripping the fabric, an elongated rigid member extending within the barrel in line with the clip and pivoted at its top end to the barrel near the open end of the latter, said pin mounted at the free end of said member, a button cooperable with said member and extending through the top open end of said barrel to actuate said member and retract said pin and spring means in the barrel urging said pin into fabric-gripping position.

2. A fabric-gripping clasp for pens, pencils and

like articles, having an open-topped barrel comprising a clip mounted spacedly on the barrel and provided at its lower end with an inner boss to contact one surface of the fabric, a pin projecting from inside the barrel just above the boss of said clip adapted to contact the other surface of the fabric, an elongated rigid member extending within the barrel in line with the clip and pivoted at its top end to the barrel near the open end of the latter, said pin mounted at the free end of said member, a button cooperable with said member and extending through the top open end of said barrel to actuate said member and retract said pin and spring means in the barrel urging said pin into fabric-gripping position.

3. In combination with a pen, pencil and similar articles having an open-ended barrel and an aperture through said barrel near the lower open end, a fabric-gripping clasp unit removably insertable into said barrel through its top end comprising a frame fitting snugly in said barrel, a clip on the outside of said frame spaced from the barrel and adapted to contact one surface of said fabric, a pin carried in said frame adapted to project through said aperture and contact the other surface of the fabric, said clip and pin cooperable to grip the fabric therebetween, an elongated rigid member extending within the barrel in line with the clip and pivoted at its top end to the barrel near the open end of the latter, said pin mounted at the free end of said member, a button cooperable with said member and extending through the top open end of said barrel to actuate said member and retract said pin and spring means in the barrel urging said pin into fabric-gripping position.

4. In combination with a pen, pencil and similar articles having an open-ended barrel and an aperture through said barrel near the lower open end, a fabric-gripping clasp unit removably insertable into said barrel through its top end comprising a frame fitting snugly in said barrel, a clip on the outside of said frame spaced from the barrel and provided at its lower end with an inner boss adapted to contact one surface of said fabric, a pin carried in said frame adapted to project through said aperture just above said boss and contact the other surface of the fabric, said clip and pin co-operable to grip the fabric therebetween, an elongated rigid member extending within the barrel in line with the clip and pivoted at its top end to the barrel near the open end of the latter, said pin mounted at the free end of said member, a button cooperable with said member and extending through the top open end of said barrel to actuate said member and retract said pin and spring means in the barrel urging said pin into fabric-gripping position.
